UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

WRAPPING MACHINE.

Application filed March 31, 1919. Serial No. 286,345.

To all whom it may concern:

Be it known that I, MICHAEL J. MILMOE, a citizen of the United States, residing at Chicago, in the county of Cook and State 5 of Illinois, have invented certain new and useful Improvements in Wrapping Machines, of which the following is a specification.

The object of the invention is to provide 10 a machine of the class named which shall be of improved construction and operation.

The invention is exemplified in the combination and arrangement of parts shown in the accompanying drawings, and described in the following specification. The invention is more particularly pointed out in the appended claims.

In the drawings—

Fig. 1 is a side elevation of a machine embodying one form of the present invention.

Fig. 2 is a top plan view of the machine shown in Fig. 1.

Fig. 3 is a front elevation of the same machine.

Fig. 4 is a rear elevation with parts in section on line 4—4 of Fig. 1.

Fig. 5 is a detail vertical sectional view substantially on line 5—5 of Fig. 3.

Fig. 6 is a similar view on line 6—6 of Fig. 3 looking in the opposite direction from that in Fig. 5.

Fig. 7 is a transverse vertical sectional view on line 7—7 of Fig. 1.

Fig. 8 is a horizontal sectional view substantially on line 8—8 of Fig. 5.

Fig. 9 is a transverse vertical sectional view on line 9—9 of Fig. 5.

Fig. 10 is a vertical section on line 10—10 of Fig. 9.

Fig. 11 is a transverse vertical sectional view showing a portion of the machine in a different position from that shown in Fig. 10.

Fig. 12 is a fragmentary vertical sectional view on line 12—12 of Fig. 2.

Fig. 13 is a top plan view of a portion of the operating mechanism with parts in section.

Fig. 14 is a view substantially on the same plane as Fig. 9 and showing a part of the mechanism of Fig. 9 on a larger scale and with parts in different positions from Fig. 9.

Fig. 15 is a vertical section substantially on line 15—15 of Fig. 14.

Fig. 16 is a vertical section substantially on line 16—16 of Fig. 14.

Fig. 17 is a perspective of a portion of the machine.

Fig. 18 is a view similar to Fig. 16 but with parts in different positions.

Fig. 19 is a view similar to Fig. 17 but showing a different phase of the operation of the device.

Fig. 20 is a view similar to Figs. 16 and 18 showing the parts in still a different position.

Fig. 21 is a vertical section on line 21—21 of Fig. 20.

Fig. 22 is a view similar to Figs. 17 and 19 but corresponding in phase to the position of the parts shown in Fig. 20.

Fig. 23 is a view similar to Figs. 16, 18 and 20 showing still a different position of the operating parts.

Fig. 24 is a vertical section on line 24—24 of Fig. 23.

Fig. 25 is a perspective view of the article being wrapped in the stage of the wrapping operation corresponding to Figs. 23 and 24.

Fig. 26 is a horizontal sectional view substantially on line 26—26 of Fig. 12.

Fig. 27 is a vertical sectional view on line 27—27 of Fig. 26.

Fig. 28 is a fragmentary vertical section on line 28—28 of Fig. 26.

Fig. 29 is a fragmentary elevation and Figs. 30 and 31 are perspective views of details.

Fig. 32 is a fragmentary vertical sectional view showing one phase of the operation of a portion of the mechanism.

Fig. 33 is a perspective of part of the mechanism shown in Fig. 32.

Fig. 34 is a view similar to Fig. 32 with the operating parts shown in a different position.

Fig. 35 is a perspective view of the parts shown in Figs. 32 and 34.

Fig. 36 is a fragmentary plan view of parts in section showing a part of the operating mechanism in the position it assumes at one phase of its operation.

Fig. 37 is a perspective view of the article being wrapped corresponding to the operating phase illustrated in Fig. 36.

Fig. 38 is a view similar to Fig. 36 showing a different phase in the operation of the machine.

Fig. 39 is a perspective view of a portion

of the mechanism shown in Figs. 36 and 38 and illustrating still a different phase of the operation of the machine.

Fig. 40 is a fragmentary vertical sectional view showing a portion of the operating mechanism.

Fig. 41 is a perspective view of part of the mechanism shown in Fig. 40.

Fig. 42 is a view similar to Fig. 40 illustrating a different phase in the operation of the machine.

Figs. 43 and 44 are perspective views of details of the machine.

Fig. 45 is a perspective view of the article 15 being wrapped at the stage illustrated in Fig. 42.

Figs. 46 to 52, inclusive, are diagrammatic views illustrating different steps in the wrapping operation.

20 While the present invention is applicable to the wrapping of a large variety of articles, it is especially adapted to wrapping butter and material having similar characteristics, the embodiment of the invention illustrated in the drawings being shown as adapted to the wrapping of butter in the form of bricks as it is commonly sold upon the market. The invention contemplates the automatic feeding of the bricks of butter to 25 the machine, the wrapping of the bricks in paraffine paper or other suitable wrappers, the formation of cartons from previously cut blanks of cardboard or similar material, the insertion of the wrapped bricks of butter in 30 the cartons thus formed, and the final closing of the cartons, the whole operation being entirely automatic and without the necessity of touching either the butter or the wrappers by the hands of the operator.

40 The operating mechanism is supported by a suitable framework designated by the numeral 1 which is provided with a pair of bearing pedestals 2 and 3, Figs. 5 and 6, in which is journaled the main driving shaft 45 4 of the machine. The shaft 4 is rotated by a driving gear 5 which meshes with a pinion 6, Figs. 1, 4 and 8, the pinion 6 being formed integral with a gear 7 carried by a shaft 8 journaled in bearings 9 and 10, the gear 7 being arranged to mesh with a pinion 11 driven by a motor 12 secured to the frame of the machine, as shown in Figs. 1, 2, 3 and 7.

50 The bricks of butter or other articles to be wrapped designated by the numeral 13 are fed to the wrapping machine along a slideway comprising a pair of angle rails 14 and 15, the bricks being placed upon the slideway in any suitable manner from the forming mechanism. The bricks are fed 55 forwardly in the slideway by a movable plate 16, Figs. 2, 9 and 10, which is preferably of wood as are also the angle bars 14 and 15 and the other parts which contact with the bricks, for the reason that wood is 60 not liable to tarnish and adheres less readily

to butter and similar substances than does metal. The plate 16 may be carried by a metal plate 17 having strengthening bars 18, and supporting blocks 19 and 20, Fig. 3, are rigidly secured to the metal plates 17 and 18. 70 The wood plate 16 is removably held in place on the metal plate 17 by spring clamps 16'. The plates are held from lateral and longitudinal movement relative to one another by pins 17' which project into openings in the bottom face of the plate 16, the openings having their inner ends rounded to prevent accumulation of foreign matter. While the machine is in operation the plate 16 is kept wet to prevent sticking of the butter thereto, and it is therefore desirable to 80 keep the plate in water when the machine is not in use to prevent injury thereto from alternate wetting and drying. The spring clamps 16' and centering pins 17' provide 85 means for holding the plate in place so that it is readily removable, and the holding means requires no screw or bolt holes or other depressions to accumulate dirt. The depression for receiving the pin 17' does not 90 go deeply into the wood and is on a face of the plate which is completely covered during operation of the machine and never comes into contact with the butter. The rails 14 and 15 are also detachably held in 95 place by spring clamps 15', similar to clamps 16', so that these rails may also be readily removed and replaced. The blocks 19 and 20 are bored, as shown in Figs. 3 and 9, to receive a rod 21 which slides longitudinally 100 through the blocks 19 and 20. Extending outwardly from the frame 1, beneath the slideway formed by the bars 14 and 15, is a channel bracket 22 for supporting the slideway and which is provided with pedestals 105 23 on which the bars 14 and 15 are mounted. The slideway and bracket 22 may be made of any desired length and provided with a requisite number of pedestals 23 throughout its length to form a proper support for the 110 slideway. The bracket 22 carries also pivot blocks 24 on which are pivotally mounted links 25 having their upper ends pivoted to the rod 21, as shown in Fig. 3. The inner end of the rod 21 is pivoted to an arm 26, Figs. 9 and 14, which is rigidly carried by a shaft 27 journaled in bearings 28 and 29 on the top plate 30 of the frame 1, as shown more clearly in Fig. 13. The end of the 115 shaft 27, opposite the arm 26, carries an arm 31 rigidly secured thereto which is pivotally connected at its outer end to a link 33, the lower end of which link is bifurcated, as shown in Fig. 9, and is positioned astride the main drive shaft 4. A cam roller 34 is carried by the link 33 and extends into a cam groove 35 on a cam wheel 36 keyed to the drive shaft 4. The rotation of the cam wheel 36 will oscillate the arm 26 and impart an up and down movement to the rod 120

125

21. The shape of the cam groove 35 is such that during approximately one-half of the revolution of the main drive shaft 4, the rod 21 will be in its uppermost position, while in 5 approximately the other half of the revolution, the rod 21 will be in a lowered position.

The block 19 which supports the plate 16 is pivotally connected with a link 37 10 carried at the upper end of an arm 38, the arm being secured to a shaft 39 journaled in bearings 40 on the frame 1, as shown in Figs. 9 and 10. On the end of the shaft 39, opposite the arm 38, is a downwardly 15 and inwardly extending arm 42 which is provided with a cam roller 43 at its inner end which travels in a groove 44 in a cam wheel 45 also secured to the main shaft 4, see also Fig. 8. The rotation of the cam 20 45 imparts a longitudinal oscillation to the plate 16 at the same time that it is vertically oscillated by the cam wheel 36 and associated mechanism. The two cams are so related that the plate 16 is moved rear- 25 wardly while in its lower position, illus- trated in Fig. 10, in which the bricks of butter 13 are permitted to rest upon the angle bars 14 and 15. During the forward movement of the plate 16, that is to the 30 right, as viewed in Figs. 9 and 14, the plate is held in its uppermost position so that the bricks are supported by the plate 16, as illustrated in Fig. 11. It will be apparent that this combined reciprocation 35 of the plate 16 will feed the bricks inwardly at each upward movement of the plate. This inward movement of the bricks continually moves the innermost one into engagement with a stop plate 46, from which 40 position the bricks are moved downwardly to be wrapped by mechanism to be described. The longitudinal reciprocation of the plate 16 is preferably of greater amplitude than the width of one of the bricks 13 so that 45 when the train of bricks is brought to a stop by the abutment plate 46, the bar 16 will still move inwardly a short distance, the bar sliding beneath the bricks for a distance equal to the excess of movement of the bar 50 over the width of the bricks. This excess movement of the bar 16 will close up any space between the bricks in the slideway, so that each movement of the bar will be sure to bring one of the bricks into position 55 against the abutment plate 46. The abutment plate 46 is provided with end wings 47 slightly curved outwardly at their free edges, as shown at 48, to guide the bricks of butter into position between the 60 wings 47. In its forward position the plate 16 carries the bricks of butter into the position shown in Fig. 9, the forward end of the plate 16 extending under the foremost brick, as indicated in that figure.

65 Wrappers 50 for the butter, consisting

of sheets of suitable material, such as parafine paper, are contained in a magazine 51, as shown in Figs. 1, 9 and 14. The magazine 51 is provided with a front plate 52 and side plates 53. The magazine is preferably open at the back, and the wrappers in the magazine are supported by projecting arms 54 and a feed roller 55, as shown best in Figs. 2 and 9. The arms 54 are carried by a cross-bar 56 supported on upright plates 57 which rest upon the frame 1 and are continuous with the side plates 53 of the magazine. As shown in Fig. 1, the side plates 53 are provided with strips 58 which slightly overlap the ends of the wrappers 50 and hold them in place in the magazine. The roller 55 is fixed to a shaft 59 which is journaled in the uprights 57 and which is provided with a sprocket wheel 60 by which it is rotated in the direction of the arrow in Fig. 14. The sprocket wheel 60 is driven by a chain 61 which extends downwardly to a sprocket wheel 62 on the main drive shaft 4, as shown in Figs. 3 and 6. The roller 55 is provided with an insert 63 of frictional material, as shown in Fig. 14, by means of which a sheet 50 is moved forwardly through the opening 64 beneath the front plate 52 of the magazine for each rotation of the roller 55. A pair of sharpened points 65 carried on brackets 66, as shown in Figs. 2 and 14, penetrate the lowermost sheets 50 to prevent more than one sheet from being extracted from the magazine at one time. In front of the opening, beneath the plate 52, is a pair of rollers 67 and 68 which engage the sheet as it is moved through the opening by the roller 55 and feed it forwardly into position beneath the forward brick 13 and the supporting plate 16, when the plate is in its innermost position, as shown in Fig. 9. The roller 67, as shown in Fig. 3, is provided with a pinion 69 which meshes with an idler 70 driven by a gear 71 on the end of the feed roller 55. The interposed idler 70 causes the two rollers 55 and 67 to rotate in the same direction. The roller 68 is fixed to a shaft 72 which is journaled in the ends of arms 73 pivotally mounted upon the sides 53 of the magazine 51. The arms 73 are pressed downwardly by springs 74 to cause the roller 68 to bear against the roller 67. On the end of the roller 68, adjacent the sprocket wheel 60, is a pinion 75 meshing with a corresponding pinion 76 on the roller 67, as shown best in Fig. 15. Secured to the front plate 52 of the magazine 51, intermediate the ends of the rollers 67 and 68, is a bracket 77 which carries a pair of rollers 78 at its lower end arranged to bear against the periphery of the roller 67, as shown in Figs. 14 and 15. The rollers 78 are pressed against the roller 67 by a spring 79 carried by a screw 80 passing through the bracket 125 130

4

77 into the front plate 52. As a sheet of paper is fed between the rollers 67 and 68, the rear edge of the paper is held against the roller 67 by the rollers 78 until the sheet is fed entirely clear of the roller 67. As the wrapping sheets are fed from between the rollers 67 and 68 a short portion of one end of a sheet passes into a slot 81 between the upper and lower bifurcations 82 and 83, respectively, of a guide member 84 supported from the machine frame, as shown in Figs. 3 and 15. The longer portion of the wrapper 50, as shown in Fig. 15, is fed onto the top of a plate 85 which is carried by a bracket 86 extending downwardly from an arm 87 supported by a bracket 88 carried by the front plate 52 of the hopper 51 and by a post 89 which is secured to the frame of the machine. A bar 90 extends inwardly over the plate 85 from the bracket 86 and forms a slot beneath its lower edge into which the sheet enters as it is fed from the rollers 67 and 68.

When a sheet has been fed into position beneath a brick, as indicated in Fig. 9, the bar 16 is withdrawn leaving the innermost brick free to move downwardly upon the sheet of paper. At the same time a supporting foot 91 is moved upwardly beneath the brick into position to engage the lower surface of the wrapper and to assist in supporting the brick of butter. While the plate 16 is being withdrawn and the supporting foot 91 is moving upwardly to press the wrapper against the lower face of the brick, the brick is supported by its frictional contact with the abutment 46 and the front face of the next adjacent brick. The supporting foot 91 is carried by an arm 92 which is secured to a cam fork 93, as shown in Figs. 6 and 9. The upper end of the cam fork 93 projects into a slot 94 in the top plate of the machine frame, while the arm 92 projects loosely through an opening 95 in the same plate. The lower end of the cam fork 93 engages a cross-shaft 96 journaled in bearings 97 and 98 which are carried by brackets 99 and 100, respectively, secured to the frame 1 of the machine, as shown best in Fig. 8. The cross-shaft 96 is driven by a beveled pinion 101 which meshes with a similar pinion 102 on the end of the main drive shaft 4. A cam 103 is keyed to the shaft 96 and is provided with a cam groove 104 in which a roller 105 on the cam fork 93 is arranged to travel. At the same time that the supporting foot 91 contacts with the lower surface of the wrapper 50 and begins to move downwardly, a presser plate 106 engages the upper surface of the same brick and forces the brick downwardly in unison with the downward movement of the supporting foot 91. The presser plate 106 is carried on an arm 107 secured to the upper end of a bar 108 which is mounted to slide vertically in a bearing 109 carried by the top plate 30 of the frame 1, as shown in Figs. 14 and 16. The plate 106 is of wood, and like the parts 14, 15 and 16 is easily removable and replaceable, having a sliding dovetail connection with its support. The lower end of the bar 108, as shown in Fig. 9, is connected with a cam fork 110 which passes astride the shaft 96 and is provided with a cam roller 111 traveling in a groove 112 in a cam 113 secured to the shaft 96. Thus the brick of butter is held between the supporting foot 91 and the presser plate 106 which move downwardly in unison so that the butter is moved from the position shown in Fig. 9 to the position shown in Figs. 14 and 16. The wrapper 50 is held from sliding relative to the brick 13 during the downward movement by the supporting foot 91 which clamps the wrapper between the upper surface of the foot and the lower surface of the brick. As the brick moves downwardly, the ends of the wrapper are drawn about the edges of the plates 83 and 85, respectively, as shown in Fig. 16, to fold the ends of the wrapper across the ends of the brick. A portion of the forward end of the wrapper, as shown in Fig. 16, will remain above the upper surface of the plate 85, but the rear end of the wrapper being of a length only slightly greater than half the height of the brick will be drawn entirely free from the plate 83. As the brick reaches its lowered position, the rear end of the wrapper engages the upper ends of a pair of uprights 114, Fig. 14, and is folded upwardly against the rear end of the brick 13, as shown in Figs. 14, 16 and 17. At the same time that the rear end of the wrapper is folded upwardly by the uprights 114, the projecting sides of the wrapper are also folded upwardly by upwardly extending flanges 115 and 116 on a pair of rails 117 and 118, respectively. It will be noted from Figs. 14 and 16 that the ends of the uprights 114 are provided with rearwardly extending lips 119, and that these lips have their outer faces inclined to permit of the formation of rear corner flaps 120 and 121 as the sides and rear end of the wrapper are folded upwardly. The flanges 115 and 116 are provided with notches 122, shown best in Fig. 13, which permit the formation of folds 123 at the forward end of the brick 13 as the brick is moved into position between the flanges 115 and 116, as shown best in Fig. 17.

After the brick has reached the position shown in Figs. 16 and 17, and the wrapper 50 has been thus far folded, it is moved forwardly by the uprights 114 which are carried upon rearwardly extending arms 124 secured to a bracket 125 by means of a screw 126. The bracket 125 is provided with a

sleeve 127 slidably mounted upon a shaft 128. See also Fig. 13. The shaft 128 is supported by brackets 129 secured to the top plate 30 of the machine frame. The bracket 125 is provided with a pin 130 on which the forward end of a link 131 is pivoted. The rear end of the link 131 is pivotally connected to a cam lever 132, Fig. 5, the lower end of the lever being carried by a pivot 133 on a bracket 134 secured to the base of the frame 1. Intermediate the ends of the lever 132 is a cam roller 135 arranged to engage a groove 136 in a cam 137 keyed to the shaft 96. It will be apparent that rotation of the cam 137 will swing the lever 132 about its pivotal support 133 and reciprocate the bracket 125 to which are connected the uprights 114. When the brick has assumed the position shown in Figs. 16 and 17, the uprights 114 will be moved forwardly carrying the brick forwardly on the rails 117 and 118. Before the forward movement begins, however, the brick will be released by the beginning of the upward movement of the presser plate 106. The forward movement of the brick will cause the forward end of the wrapper which has until this time been drawn about the edge of the plate 85, as shown in Fig. 16, to be folded backwardly over the upper surface of the brick, as indicated in Figs. 18 and 19, and at the same time that the end of the wrapper is being folded over the top of the brick, the edges of the grooves 122 will turn the folds 123 backwardly so that the folds will be drawn through the grooves into the position shown in Fig. 19. It is apparent that the movement of the folds 123 could not take place prior to the folding of the wrapper backwardly over the top of the brick without danger of tearing the wrapper on the line about which it is turned over the edge of the plate 85. However, the grooves 122 are of sufficient width that the movement of the folds 123 follows closely after the rearward folding of the upper part of the wrapper.

A pair of risers 138 project upwardly from the flanges 115 and 116 at a point along the slide rails reached by the forward end of the brick after the wrapper has been folded against the upper surface of the brick for a distance somewhat greater than the distance that the wrapper projects laterally from the upper face of the brick. When the forward end of the brick reaches the risers 138, the projecting portions of the wrapper above the folds 123 will be smoothed backwardly against the sides of the brick, as shown in Fig. 19. As the brick continues to move from the position shown in Fig. 19, the edges of the wrapper which project laterally from the upper surface of the brick are engaged by the inclined edges 139 of folder plates 140 so that the projecting edges are folded downwardly against the sides of the brick, as shown in Figs. 20, 21 and 22. In Fig. 20 the upright pushers 114 are at their extreme forward position, and the rear edge of the brick of butter is opposite an opening 141 in the top plate 85. The shape of the opening 141 will be apparent from Fig. 2. The plate 85 in front of the opening 141 does not extend entirely across the top of the slideway, but is cut away to provide a slot 142, shown in Figs. 2, 21 and 24.

After the upright pushers 114 have begun their rearward movement from the position shown in Fig. 20, a second pusher 143, Figs. 23 and 24, is moved downwardly into position adjacent the rear end of the brick, and as it moves downwardly it folds the rearwardly projecting portion of the wrapper against the rear end of the brick so that the wrapper is now folded about the brick in the manner shown in Fig. 25. Extending forwardly from the upper edge of the pusher 143 is a beveled flange 144 which engages the upper face of the brick near the rear end, as shown in Fig. 23, and compresses that portion of the brick to form a slightly beveled portion shown at 145 in Fig. 25. A similar beveled portion 146 is formed at the diagonally opposite corner of the brick by the upper face of the slide rail 15, as shown at the upper left-hand portion of Fig. 23. The purpose of these beveled corners will appear later. The pusher 143 is carried on an arm 147 which is pivotally mounted upon a sleeve 148, the sleeve being slidably carried on a rod 149. The sleeve 148 is provided with a downwardly projecting lug 150 to which a link 151 is pivotally connected. The rear end of the link 151 is pivoted to a cam lever 152, Fig. 5, which is provided with a cam roller 153 engaging a cam groove 154 in the side of the cam 137 opposite the groove 136. Rotation of the cam 137 reciprocates the pusher 143 in proper timed relation with the upright pushers 114. The end of the arm 147, opposite the pusher 143, is pivotally connected to a cam rod 155 which slidably engages a cylindrical bar 156 carried by a bracket 157 secured to the arm 147. The cam rod 155 is held against lateral movement by a casing 158 secured to the top plate 30 of the frame. The lower end of the rod 155 is bifurcated, as shown in Fig. 7, and straddles the main drive shaft 4. The rod is provided with a cam roller 159 which operates in a groove 160 in a cam 161 keyed to the shaft 4. Rotation of the cam 161 oscillates the arm 147 about the shaft 149, and the cam groove 160 is so shaped that the pusher 143 is moved downwardly through the opening 141 in the top plate 85 while the arm

147 is held stationary as to its movement along the shaft 149. As clearly shown in Fig. 24, the arm 147 is provided with a gooseneck adjacent the pusher 143 which permits it to extend over the inclined folder 140 and through the slot 142 so that the pusher 143 is carried in contact with the rear end of the brick 13 during the forward movement of the pusher along the slideway 10 formed by the rails 117 and 118. During the forward movement of the pusher plate 143 it is not oscillated by the cam rod 155 about the shaft 149, but remains stationary as to vertical movement until it reaches the 15 forward end of its path of movement, at which time it passes out from beneath the forward edge of the plate 85. The arm 147 is then oscillated about the shaft 149 to raise the pusher plate 143 above the cover 20 plate 85, after which the arm and pusher plate are drawn backwardly by the link 151 into their initial position. The forward movement of the pusher plate 143 carries the butter from the position shown in Fig. 23 25 entirely into the carton shown at 162 which has previously been formed and arranged in position to receive the wrapped brick, as shown in Fig. 23. Fig. 36 illustrates the pusher 143 in the act of forcing the brick 30 13 into the opened carton, and Fig. 37 is a perspective of the carton with the brick partially in place.

The cartons are supplied to the machine in the form of blanks, shaped as illustrated 35 in Fig. 2. Each carton is formed with five side walls *a*, *b*, *c*, *d* and *e*. The side wall *a* is provided with an end flap *f*; the side wall *b* with an end flap *g* and a tucking flap *h*; the side wall *c* with two end flaps *i* and *j*; the side wall *d* with an end flap *k* and a 40 tucking flap *m*; and the side wall *e* is provided with two end flaps *p* and *q*. The blanks for the cartons 162 are laid upon conveyer chains 163 which carry the blanks 45 toward the center of the machine, as shown in Figs. 2 and 5. The chains 163 pass over sprocket wheels 164 and 165 at their forward ends, the rear ends of the chains being carried by similar sprocket wheels supported 50 upon rearwardly extending angle bars 166 along which the blanks 162 are moved by flights 167 on the chains 163. The sprocket wheels 164 are secured to a shaft 168 journaled in the frame of the machine and provided with a sprocket wheel 169 which is 55 driven by a chain 170 guided over suitable idlers 171 and meshing with a sprocket wheel 172 carried by the end of the cross-shaft 96, as shown in Figs. 3 and 8. The 60 machine frame 1 is provided with a top plate 173 which carries a pair of rails 174 and 175, Figs. 4 and 6, and these rails are provided with slots in their outer faces in which a pair of rack bars 176 slide. The

rails 174 and 175 are cut away, as shown in Fig. 6, to permit engagement of the teeth of the racks by the teeth on gear wheels 177. The gear wheels 177 are fixed to a shaft 178 which is centrally provided with a pinion 179, Figs. 4 and 6, the teeth of which mesh with the teeth of a rack 180. The rack 180 is attached to a cam fork 181 which straddles the main drive shaft 4 and carries a cam roller 182 working in a groove 183 in a cam 184 on the shaft 4. Rotation of the shaft 4 imparts a reciprocation to the rack 180 which is transmitted to the two racks 176. Each of the racks 176 is provided at its forward end with a finger 185 having its front end notched, as shown in Fig. 5, for the purpose of engaging the rear edge of the carton blank. As will be seen best from Fig. 6, the angle supports 166 for the blanks 162 are provided with a downwardly inclined portion slightly in the rear of the forward run of the conveyer chains 163. Because of this inclination in the supports for the blanks, the fingers 185 in their retracted position will be below the blanks 162, but after a blank has moved downwardly along its inclined support, its rear edge will come into a position on a level with the notches in the fingers 185, so that the fingers will engage the rear edges of the blanks during their forward movement and carry the blanks into folding position, which is the position occupied by the blank in the central portion of the drawing in Fig. 2. The forward movement of the fingers 185 is sufficiently rapid to carry the blanks away from the flights 167 and prevent downward bending of the edges of the blanks as the chains pass over the sprocket wheels at the forward end of their run.

Slidably mounted in bearings 186 and 187, Figs. 2, 7 and 12, on a bracket 188 is a rod 189 which carries an arcuate hook 190 at its forward end. The rod 189 has an arm 191 rigidly secured thereto, and a link 192 is pivoted to the end of the arm 191 and to the upper end of a lever 193. The lever 193, as shown in Fig. 4, is pivotally mounted on a shaft 194 carried by brackets 195 and 196 secured to the side of the machine frame 1. The lever 193 is pivotally connected at its lower end, as shown in Figs. 4 and 8, with a cam rod 197 which straddles the main drive shaft 4 and is provided with a roller 198 traveling in a groove 199 in a cam 200 secured to the shaft 4. Rotation of the cam 200 reciprocates the rod 189 in its bearings 186 and 187 which imparts a similar reciprocation to the hook 190 on the end of the rod. As shown in Figs. 12, 32 and 38, a pair of angle bars 201 are carried at the end of a pair of arms 202 in position to form a continuation of the outermost angle bar 166 on which the carton blanks are fed.

to their central or folding position. The other angle bar 166 has its inner end in alignment with an extension 203 on the bracket 188, the extension 203 having its edge curved, as shown at 204, to overlie the edge of the blank 162 as it is pushed from the end of the angle bar 166 by the fingers 185. The edge of the blank 162, adjacent the extension 203, is supported by a plate 205 provided with a downwardly extending portion 206. The plate 205 is secured to and supported from the projection 203. The angle bars 201 and their supporting arms 202 are spaced from one another to provide a slot in which the hook 190 travels, and this hook is in the position illustrated in Fig. 12 when the blank 162 is fed into its folding position by the fingers 185. The forward arm 207 of the hook 190 extends below the level of the blank 162, and the rear arm 208 terminates slightly above the upper face of the blank. After the blank is in the position shown in Fig. 12, the rod 189 is drawn inwardly and the edge of the blank strikes the inner curved surface of the hook 190, and since the blank is held by the curved abutment 204, the blank will be caused to bend along the scored lines by which the sides *a*, *b*, *c*, *d* and *e* are separated, so that the blank will roll into the form shown in Figs. 32 and 33. This will bring the side *c* so that its outer face is just inside the plane of the inner face of the plate 209 which supports the arms 202, and which with the plate 206 forms the walls of a filling pocket for the carton.

A pair of forked members 210 are supported by downwardly extending rods 211 carried on an arm 212, the rods 211 being located on opposite sides of the bar 189, as shown in Figs. 2 and 5. The arm 212 is connected to the upper end of a vertically moving bar 213 which slides in bearings 214 and 215, Fig. 4. A collar 216 is fixed to the bar 213 and is connected by a link 217 with a lever 218 pivoted on a pin 219 on the frame of the machine, as shown in Figs. 7 and 8. Each of the forks 210 is provided with a long prong 220 and a short prong 221. When the carton is rolled into folded position it will pass beneath the short prong 221, as shown in Fig. 32, but will strike the lower end of the long prong 220. When the carton reaches the position shown in this figure, the forks 210 will begin to move downwardly and will carry the carton with it in the manner illustrated in Fig. 34 into the filling pocket. As the carton moves downwardly, the side wall *e* will be folded by the inclined corner between the plates 205 and 206 inwardly against the outer face of the prongs 220, as shown in Fig. 34. A pair of hooks 222 are pivoted at 223 on each side of the plate 206 and have their rear faces connected by

a bar 224 which is pressed inwardly by a spring 225 having its rear end abutting against a bracket 226 carried by the plate 205. The downwardly moving carton forces the hooks 222 backwardly against the tension of the spring 225 until the carton has passed the shoulders of the hooks, at which time the hooks spring inwardly and hold the carton in place during the upward movement of the fork 210. The prongs 221 of the forks 210 are sufficiently separated to pass on opposite sides of the plate 209, as illustrated in Fig. 34. The plate 209, as shown in Fig. 12, is secured by screws 227 to a block 228 which is carried on standards 229 and 230, the block being provided with a rearwardly extending plate portion 231 which rests upon the standards 230. The block is removably held in place on the standards 229 by a cross-bar 232, and the plate 231 is removably secured to the standards 230, see Fig. 26, by arms 233 connected with sleeves 234 mounted on pivot pins 235. The arms 233 are pressed outwardly by springs 236, and the upper ends of the sleeves 234 are connected with hand grips 237, by means of which the arms 233 may be swung inwardly against the tension of the springs 236 and freed from slots in the upper ends of the standards 230 to release the block 228 so that it may be removed from the machine frame. The bar 232 is held in place by screws at its ends, and is also removed prior to the removal of the block 228. The block 228 and plate 231 are made thus easily removable in order to give ready access to the parts adjacent the filling pocket. A pair of bracket bars 238, Figs. 26 and 32, are secured by screws 239 to the sides of the block 228 and carry a pivot shaft 240 at their outer ends. A pair of fingers 241 are fixed on the ends of the shaft 240 in position to swing vertically along the edges of the plate 209. The ends of the fingers 241 when swung in to their uppermost position engage the carton at the side opposite the hooks 222 as the carton is moved downwardly by the forks 210, thus equalizing the resistance to the downward movement of the carton and preventing distortion of the carton as it is moved into the filling pocket. In order to provide a uniform resistance to the downward movement of the fingers 241, the central portion of the shaft 240, Figs. 12 and 26, is provided with a brake segment 240 which is secured to the shaft 240 to turn with the fingers 241. A brake shoe 243 bears against the segment 242 under the pressure of a spring 244 housed in the block 228. A link 245 is pivoted at 246 to the segment 242 and is provided with a slot 247 through which a pin 248 passes. The pin 248 is connected with a reciprocating member 249, operated in a manner to be described, so that it causes

the pin to engage the end of the slot 247 at the proper time in the operation of the machine to restore the fingers 241 to their uppermost position after a carton has been filled and moved out of the filling pocket.

A plate 250, as shown in Fig. 12, extends transversely of the machine beneath the filling pocket and forms a slideway onto which the filled cartons are lowered in a manner to be described, and along which they are moved from the machine after the end flaps of the carton have been closed. A plunger 251 is mounted to reciprocate above the plate 250 and is provided on its upper face with rearwardly projecting fingers 252, see Fig. 30, which form the support for the carton while in filling position, as shown in Fig. 12. The plunger 251 is connected with the forward end of a reciprocating bar 253, the rear end of which bar is connected by a link 254 with a cam lever 255. The cam lever 255 is pivotally mounted on the shaft 194 and is rigidly connected with an inwardly projecting arm 256 which carries a roller 257 at its inner end, Figs. 7 and 8, arranged to bear in a groove formed in the face of a cam 258 secured to the shaft 4. Rotation of the cam 258 reciprocates the plunger 251 to perform its various operations, as will be described.

While the carton is held in the filling position and supported by the plunger 251, the brick of butter which has been wrapped in the manner previously described is forced into the carton from the left, as viewed in Fig. 23, which is the same as the lower side of the drawing in Fig. 36. In order to hold the carton from sliding during the time that the butter is being forced into it a finger 259 is caused to bear upon the flap *k*. The finger 259 is fixed to a rock shaft 260 which has an arm 261, Figs. 5, 9 and 27, secured thereto, the arm being connected with a cam rod 262 which carries a roller 263 at its lower end arranged to operate in a groove 264 in the cam 45. After the carton has been folded and moved into the filling position, the shaft 260 is rocked to cause the finger 259 to grip the end flap of the carton, as shown in Fig. 23. The rod 262 is made in two parts having an interposed spring 262' to render, resilient, the gripping action of the finger 259.

After the brick of butter is moved into the carton, the end flaps are closed by mechanism which is shown in Figs. 26, 36, 38 and 39. A rod 265 is mounted to slide in the block 228 and in a bearing 266 projecting upwardly from the outer end of the plate 23. The rod 265 has fixed thereto the member 249 which carries laterally projecting arms 267 and 268. Pivotally mounted at the end of the arm 267 is a lever 269 which carries a flap-closing plate 270 at one end and which is provided with a pin 271 projecting

downwardly from the other end. The pin 271 is arranged to travel in a cam slot 272 formed in a plate 273 which is fixed to the upper surface of the plate 231. The arm 268 carries a lever 274 provided with a flap-closing plate 275 and a pin 276 arranged to travel in a cam slot 277. Both of the levers 269 and 274 are provided with spring-pressed brakes 278, as shown in Fig. 36, to hold their respective levers in any angular position into which they are turned until they are positively moved from that position. The rod 265 is slid longitudinally in its supports by a sleeve 279 which has a limited rotary movement about the rod, as shown in Fig. 27, but which is held against longitudinal movement by a collar 280. The member 249 is held from rotation about the rod 265 by a bar 281 mounted on the plate 231, as shown in Fig. 27. The sleeve 279 carries an arm 282 provided with a socket 283 at its outer end, the lower side of the socket being open so that it may be swung into and out of engagement with a pin 284 on a lever 285, as shown in Figs. 26 and 27. The lever 285, as shown in Figs. 7 and 8, is pivotally mounted on a pin 286 carried on a bracket 287 secured to the frame of the machine. The lower end of the lever is provided with a cam roller 288 which engages a groove 289 in a cam 290, Fig. 6, keyed to the shaft 4. Rotation of the cam 290 reciprocates the rod 265 which carries with it the arms 267 and 268 and their respective flap-closing plates. It should be noted that the plate 270 extends inwardly a greater distance than the plate 275, as shown in Fig. 36, and the forward movement of the rod 265 causes the pin 271 to travel along the inclined wall 291 of the groove 272 to cause the plate 270 to be swung into the position shown in Fig. 36, closing the end flap *i* of the carton. The parts reach the position shown in Fig. 36 prior to the filling of the carton so that the plate 270 assists in holding the carton in place during the movement of the brick 13 into the carton. The plate 275 does not engage the end flap *j* until the carton has been filled and the pusher 143 raised out of engagement with the end of the brick. It should be noted that the plates 270 and 275 when they first strike their respective flaps are in their outer position and are moved inwardly by the inclined portions of their cam grooves after the front edges of the plates have come into contact with the flaps to be closed. Fig. 38 shows both plates 270 and 275 moved to their innermost position holding their respective flaps closed, while at the left of the figure, corresponding plates 292 and 293 are shown in the act of closing the flaps *p* and *q* on the other side of the carton. It will be seen that the folding of the end flaps of the carton carry inwardly with them the end folds 130

on the paper wrapper, thus completing the wrapping operation simultaneously with the folding of the end flaps. The flaps at one side of the carton are folded slightly in advance of the flaps on the other side, as shown in Fig. 38, so that the end flaps are made to overlap one another. The plates 292 and 293 are carried respectively by arms 294 and 295 pivotally mounted on projections 296 and 297 on a sleeve 298 fixed to the end of a sliding rod 299. The rod 299, as shown in Fig. 12, slides in bearings 300 and 301 carried on the frame of the machine and is reciprocated by a lever 302 connected to the rod by a link 303. The lever 302 is pivotally mounted, as shown in Figs. 7 and 8, upon the shaft 194, and its lower end 304 projects inwardly and carries a cam roller 305 which travels in a groove 306 in the cam 290. The arms 294 and 295 are provided with pins 307 which project into cam grooves 308 formed in plates 309 carried at the sides of the bearing block 300. A link 310 is pivotally mounted at 311 on the arm 295 and is provided with a slot 312 in its opposite end through which a pin 313 extends into the arm 294. The pin 313 is surrounded by a coil spring 314 and bears upon a washer 315 to produce frictional engagement between the arm 294 and the link 310. During the inward movement of the arms 294 and 295 they travel in a straight line in their outermost positions until the front ends of the plates 292 and 293 have engaged the flaps and begun their closing movement. Further movement of the arms causes them to travel along the inclined portions of their cam grooves which swings the plates 292 and 293 inwardly to close the end flaps, as shown in Fig. 39. The return movement of the arms will carry the plates in a different path from that traveled during their inward movement, for they will be held in their closed position by the friction between the link 310 and the arm 294, so that they will travel backwardly in a straight line until they have been withdrawn from engagement with the closed flaps, at which time the pins 307 will again strike an inclined portion in the cam grooves, and the plates will be opened ready for a second operation. The plates 270 and 275 follow a similar path of movement due to the shape of their cam grooves and the brake members 278 arranged at the pivotal connection between the levers 269 and 274 and their supports.

Before the plate 292 is entirely withdrawn from engagement with the flap *g*, the overlapping end flap *g* is swung downwardly to hold the flaps *g* and *i* in place. The movement of the flap *g* is produced by a finger 316, Figs. 40 and 42, pivotally mounted at 317 on a rocker arm 318. The finger 316 is provided with a cam roller 319 which bears upon a cam 320 carried on the plate 173 of

the machine frame. A spring 321 normally forces the finger 316 upwardly and the cam roller 319 downwardly into engagement with the upper face of the cam 320. Rotation of the arm 318 in the direction of the arrow in Fig. 40 carries the finger 316 inwardly from the position shown in Fig. 42 to that shown in Fig. 40. Further movement of the arm in the same direction causes the roller 319 to travel along the steeper part of the cam 320, so that the end of the finger is moved downwardly in an almost vertical line to close the flap *g* against the end of the carton. The arm 318 is secured to a shaft 322 journaled in the sides of the machine frame, as shown in Fig. 4, and provided with an arm 323, Fig. 6, the end of which is pivoted to a link 324 having a cam fork 325 at the opposite end which straddles the shaft 96. The cam fork 325 is provided with a roller 326 which engages a groove 327 in the cam 103 secured to the shaft 96.

After the carton 162 has been filled and the flaps closed, as described, the plunger 251 is withdrawn from beneath the carton 90 and the carton is moved downwardly onto the plate 250. During the downward movement of the carton it is supported by a U-shaped plate 328, the legs 329 of which project upwardly to engage the ends of the carton on opposite sides of the plunger 251, as shown in Fig. 40. The plate 328 is supported by a bar 330, Fig. 5, which carries a cam roller 331 at its lower end arranged to engage a cam groove 332 in the cam 258. Secured to the lower surface of the plate 328, as shown in Fig. 12, is a bracket 333 having a pair of arms 334 pivoted thereon and connected by a cross-plate 335. A lever 336 projects downwardly from the cross-plate 335 and is provided with a cam roller 337 at its lower end, as shown in Fig. 7. The roller 337 operates in a groove formed in an upright bar 338 which is rigidly carried by a rod 339 mounted to slide in a bearing bracket 340 and a bearing sleeve 341 carried by the frame of the machine. The end of the arm 339 is connected by a link 342 to the lever 255 which operates the plunger 251. The upper ends of the arms 334 are provided with hooks 343 arranged to be swung into engagement with the upper face of the filled carton when the plate 328 is in its uppermost position and the carton is in the filling pocket. As the plunger 251 is withdrawn from beneath the filled carton, the hooks 343 will be swung inwardly, as will be apparent from Fig. 7, to cause the hooks to engage the upper face of the filled carton when the plunger has been withdrawn from beneath it. This will leave the carton resting upon the upper edges of the legs 329 of the U-plate 328 with the hooks 343 holding the carton in place upon the U-plate, as illustrated in Figs. 40 and 41.

When the parts are in this position, the bar 330 is lowered by the rotation of the cam 258, and the U-plate 328 and hooks 343 move downwardly in unison with one another to lower the filled carton out of its filling pocket. It will be apparent from Fig. 40 that during the lowering movement of the carton, the end flap *k* will be folded inwardly by the rounded ends of the slide rails 117 and 118. At the same time the flap *g*, which has been closed by the finger 316, will pass within the outwardly turned upper edge 344 of a plate 345 secured to the end of a bar 346, and shown in perspective in Fig. 43. The bar 346 is supported by the standards 229 and 230, as shown in Fig. 12, and extends parallel to the slide plate 250 to form a guide for one end of the cartons as they are slid out of the machine. When the filled carton is brought into engagement with the upper face of the plate 250, the end flaps will be held closed, as shown in Fig. 42, and the carton will rest upon the plate 250 in front of the plunger 251 so that a second forward movement of the plunger will carry the carton 162 into the position at the right of the plunger in Fig. 12, which shows the plunger just before it has reached its extreme inner position. After the plunger has reached its extreme movement to the right, as viewed in Fig. 12, it will leave the inner face of the carton in alignment with the inner face of the plate 209, in which position the flaps *m* and *h* are tucked into place, which is the last operation to be performed.

The mechanism for tucking the flaps *m* and *h* is shown in Figs. 27 to 31, inclusive, and the steps of the tucking operation are illustrated diagrammatically in Figs. 46 to 52, inclusive. Fig. 46 shows the carton in the condition in which it is left by the plunger 251 when it is pushed away from beneath the filling pocket into the slideway above the plate 250. A pair of levers 347 and 348 are pivotally mounted at 349 and 350, respectively, on opposite sides of the slideway, and the lever 347 is provided with a series of downwardly projecting fingers 351 for engaging the tucker flap *m* of the end flap *k*, while the lever 348 is similarly provided with upwardly projecting fingers 352 for engaging the tucker flap *h* of the end flap *g*. The pivot 349 for the lever 347 is carried by the bracket 353 which supports the ends of the slide rails 117 and 118. The pivot 350 for the lever 348 is carried on a support 354 secured to the top plate of the machine frame, as shown in Fig. 13. The lever 348 is provided with a coil spring 355 which normally raises the rear end of the lever into engagement with a stop 356 which throws the fingers 351 downwardly into the position shown in Fig. 46. A similar spring 357 throws the forward end of the lever 347

upwardly holding the fingers 352 in the position shown in Fig. 46. The rear ends of the levers 347 and 348 are provided with pins 358 and 359, respectively, the pin 358 being located in position to strike the upper beveled surface of a bar 360 projecting rearwardly from the plunger 251. The pin 359 is similarly arranged in position to strike the lower beveled surface of a bar 361 projecting rearwardly from the opposite side of the plunger. When the plunger is in its forward position, as shown in Fig. 29, the front ends of the levers 347 and 348 with their fingers 351 and 352 will be held in retracted position by the springs 355 and 357, but when the plunger 251 is moved backwardly from beneath the filling pocket, the bars 360 and 361 will strike the pins 358 and 359 and force the fingers 351 and 352 inwardly into the position illustrated in Fig. 49.

Cooperating with the fingers 351 and 352 are tucker hooks 362 and 363, the hooks being spaced apart, as shown in Fig. 31, to permit the fingers 351 and 352 to enter the spaces between the hooks. The hooks 362 are carried on a block 364 secured to the front end of a slide 365 which is supported on the upper face of the top plate 30 and held in place by guides 366, Fig. 13. The hooks 363 are similarly carried by a block 367 secured to the end of a slide 368 which is held in place on the top plate 30 by guides 369. The lower faces of the slides 365 and 368 are provided with lugs 370 having rectangular blocks 371 pivotally carried thereby. A bracket 372 is secured to the machine frame 1, as shown in Fig. 28, and carries a pair of bell crank levers 373 pivotally mounted thereon. The upper ends of the levers 373 are bifurcated to engage the pivot blocks 371 of the slides 365 and 368. The lower arms of the levers 373 are similarly bifurcated to engage pivot blocks 374 carried by the upper end of a vertically reciprocating bracket 375, shown also in Fig. 7. The bracket 375, as shown in Fig. 6, is formed integral with the cam fork 376, which straddles the main drive shaft 4, and is provided with a cam roller 377 which travels in a groove 378 in a cam 379 secured to the shaft 4. Rotation of the cam 379 oscillates the bell crank levers 373 about their pivots and reciprocates the slides 365 and 368 in their guides. The bifurcated ends of the bell crank levers 373 are given sufficient sliding movement upon their rectangular pivot blocks to compensate for the arcuate movement of the ends of the bell crank levers. The timing of the movement of the fingers 351 and 352 relative to the tucker hooks 362 and 363 will best be understood from Figs. 46 to 52, inclusive. It should be noted in these figures that the bar 346 which bears against the upper right-hand corner

of the carton is rounded at its lower inner edge, as shown at 380, and that a guide plate 381 which engages the lower left-hand corner of the carton is similarly rounded at 382. 5 The guide plate 381 is secured to the slide plate 250, as shown in Figs. 28 and 32. After the carton is moved from the position indicated in Fig. 42 to a position in alignment with the operating parts of the tucking 10 mechanism to the right of the filling pocket, as viewed in Fig. 12, the parts will be in the relative position shown in Fig. 46. The tucking hooks 362 and 363 will then be moved inwardly, as indicated in Fig. 47, to 15 fold the tucking flaps *m* and *h* inwardly over the edges of the side walls *b* and *d*, the flaps being folded against the outer faces of the side walls. When the hooks 362 and 363 reach their innermost positions, the shoulders 20 383 on the ends of the hooks will engage the edges of the tucker flaps, which action will be assisted by the resiliency in the flaps, which tends to spring them outwardly into contact with the shoulders. The 25 tucker flaps are provided with beveled portions 384 which press against the folded portions of the flaps and assist the tendency of the flaps to spring outwardly. As soon as the flaps are engaged by the shoulders 383, 30 the tucker hooks are then withdrawn into the position shown in Fig. 48. This will spring the end flaps *g* and *k* backwardly, but the resiliency of the end flaps will hold the tucker flaps in engagement with the shoulders 383. The rounded portions 380 and 382 of the guide members 346 and 381 assist 35 in this springing tendency of the end flaps. By the time the parts are in the position shown in Fig. 48, the plunger 251 has been 40 sufficiently retracted to bring the beveled ends of the bars 360 and 361 into engagement with their respective pins 358 and 359, so that the levers 347 and 348 are oscillated to move the fingers 351 and 352 inwardly to 45 force the tucker flaps *m* and *h* past the edges of the side walls *b* and *d*, as shown in Fig. 49. During this inward movement of the fingers 351 and 352, the tucker hooks remain stationary and the fingers push the edges of 50 the tucker flaps free of the shoulders 383. The inward movement of the fingers 351 and 352 brings the tucker flaps more nearly into a horizontal position so that the edges of the flaps will free themselves from the notches 55 in the ends of the fingers. This will permit the tucker flaps to spring inwardly into the position shown in Fig. 50, the fingers 351 and 352 holding the flaps sufficiently within the plane of the side walls *b* and *d* to make 60 sure that the edges of the flaps will not strike the edges of the side walls. As has been previously stated, the diagonally opposite corners of the brick of butter were beveled off by the slide bar 15 and the flange 144 so 65 that sufficient space is provided to insure the entrance of the tucker flaps *m* and *h* between the side walls of the carton and the surface of the brick of butter. To insure the movement of the tucker flaps into the space thus provided, the blocks 364 and 367 are given 70 a slight movement inwardly into the position shown in Fig. 50 to start the tucker flaps into place in case the resiliency of the end flaps fails to perform this movement. By the time the parts have reached the position shown in Fig. 50, the plunger 251 has 75 reached its extreme outer position and has begun to move inwardly again to engage the next carton, so that the pins 358 and 359 are freed from the bars 360 and 361, and the fingers 351 and 352 are consequently again moved outwardly into the position shown in Fig. 51. This permits the tucker flaps *m* and *h* to spring outwardly into contact with the inner face of the side walls *b* and *d*, and 80 to facilitate this outward movement of the tucker flaps the blocks 364 and 367 are backed away slightly from engagement with the end flaps so that the flaps are left free and unrestrained to assume the position 85 shown in Fig. 51. The parts remain in the position shown in Fig. 51 only momentarily, after which the blocks 364 and 367 again move inwardly to the position shown in Fig. 52 and force the tucker flaps completely 90 home within the side walls of the carton. This movement completes the wrapping operation and the blocks 364 and 367 are withdrawn from engagement with the ends of the 95 carton in time to permit the completely wrapped brick and carton to be moved out of the way along the slide plate 250 as the next carton is being moved into the tucking position by the plunger 251. The finished 100 cartons are thus continuously forced outwardly along the slide plate 250 away from the machine where they are received and packed ready for shipment. The carton requires no gluing, for the reason that the end flaps are held in place by the tucker flaps and the outermost overflapping side wall *e* is provided with end flaps *p* and *q* at each 105 end which when bent inwardly and enclosed by the other end flaps prevent the outer side wall *e* from becoming unfolded. 110

The operation of the various parts has been described in connection with the description of the parts, and it is thought that further description of the operation, as a whole, will be unnecessary. It will be apparent that the operation of the machine is continuous and that the bricks of butter are wrapped and placed in cartons entirely automatically without the necessity of the wrappers or bricks being touched by the hands 115 of operators.

I claim:—

1. In combination, a support for a series of articles to be wrapped, means for feeding a wrapper beneath said support, means for 120

125

130

moving said support in a direction substantially parallel with the plane of said wrapper to feed the endmost article of said series into position to be discharged from said support and for subsequently moving said support in a reverse direction to withdraw said support and to permit movement of said article into position upon said wrapper, and means for holding the said series of articles against backward movement during the withdrawal of said support.

2. In combination, a support for a series of articles to be wrapped, means for feeding a wrapper beneath said support and above a wrapper supporting member, means for shifting said support in a direction substantially parallel with the plane of said wrapper to position said article over said wrapper, means for withdrawing said article support to permit the endmost article of said series to move into engagement with said wrapper and to hold said wrapper between said article and said wrapper support, and means for holding said series of articles against backward movement during the withdrawal of said support.

3. In combination, a support for a series of articles to be wrapped, means for feeding a wrapper beneath said support, means for shifting said support with said article thereon in a direction substantially parallel with the plane of said wrapper to position one of said articles over said wrapper, means for withdrawing said support from beneath the said one of said articles, and means for engaging said article to move said article downwardly into engagement with said wrapper.

4. Mechanism for wrapping articles comprising means for supporting a substantially horizontally arranged series of articles to be wrapped, means for feeding a wrapper into position adjacent one of said articles, means for engaging said wrapper on one side of said article, means for engaging said article at the side opposite said wrapper while said article is in alignment with the other articles in said series, and mechanism for moving said wrapper-engaging means and said article-engaging means laterally relative to said series of articles and in unison with one another to carry said article out of said series while in contact with said wrapper.

5. In combination, a support for a substantially horizontally arranged series of articles to be wrapped, means for feeding a wrapper into position beneath said support adjacent one of the articles in said series, means for withdrawing said support to permit said article to be moved into engagement with said wrapper, means for supporting portions of said wrapper beyond the edges of said article, and means for moving said article relative to said wrapper-supporting

means while in engagement with the portion of said wrapper intermediate said wrapper-supporting means to cause said wrapper to be folded about said article.

6. In combination, a support for a substantially horizontally arranged series of articles to be wrapped, means for feeding a wrapper beneath said support adjacent an article of said series, means for withdrawing the support from beneath said article to permit said article to move downwardly into engagement with said wrapper, and means for engaging the upper surface of said support for positively moving said article downwardly against said wrapper.

7. The combination with a pair of spaced supports, of means for feeding a wrapper onto said supports to bridge the space therebetween, movable means for engaging the wrapper between said supports, means for depositing an article to be wrapped upon the portion of the wrapper between said supports while said wrapper is positioned on said supports, means for engaging the upper face of said article to press said article downwardly upon the upper face of said wrapper, and mechanism for moving said article-engaging means and said movable wrapper support in unison with one another to force said article downwardly between said spaced wrapper supports and cause the overlapping portions of said wrapper to be folded against the upright sides of said article.

8. In combination, a pair of spaced supports, means for feeding a wrapper onto said supports to bridge the space therebetween, a movable member for supporting said wrapper between said spaced supports while said wrapper is in position to bridge the space between said supports, a movable support for carrying an article to be wrapped into position above the portion of said wrapper which bridges the space between said wrapper supports, means for withdrawing said movable support to permit said article to move downwardly onto the upper face of said wrapper, means for engaging the upper face of said article to positively move said article downwardly onto said wrapper and to cause said wrapper to be held between the lower face of said article and said movable member for supporting said wrapper, and mechanism for moving said article-engaging means and said movable member downwardly relative to said spaced wrapper supports to cause the overlapping portions of said wrapper to be folded upwardly against the upright faces of said article.

9. In combination, means for supporting an article to be wrapped, means for positioning a wrapper beneath said article, a pair of members arranged to clamp said wrapper and said article to be wrapped in contact

with one another between said members, mechanism for moving said clamping members transversely to the plane of said wrapper to bring said wrapper and article into engagement with one another and to subsequently move said article and wrapper together in a direction transverse to the plane of said wrapper, and means for engaging portions of said wrapper extending beyond the face of said article engaged by said wrapper to cause said portions to be folded against adjacent faces of said article.

10. In a wrapping machine, mechanism for bringing an elongated article into engagement with an elongated wrapper so that the axis of said article and said wrapper extend in the same direction and so that said article engages said wrapper at one side of the transverse central axis of said wrapper, means for moving said article transversely to the plane of said wrapper to fold the central portion of said wrapper against one end of said article, means for moving said article in the direction of its longitudinal axis and toward the end engaged by the central portion of said wrapper, means for engaging projecting portions of said wrapper during said movement to fold said projecting portions backwardly against longitudinal faces of said article so that the opposite ends of said wrapper will extend beyond the end of said article opposite that engaged by the central portion of said wrapper, and means for folding said projecting ends of said wrapper inwardly over the end of said article opposite that engaged by the central portion of said wrapper.

11. In a wrapping machine, mechanism for bringing a wrapper into engagement with one surface of an article to be wrapped and for moving said article transversely to the plane of said wrapper, means for engaging a projecting portion of said wrapper during said transverse movement to fold said projecting portion against the side of said wrapper normal to the side first engaged by said wrapper, and means for engaging a portion of said wrapper projecting from the side of said article first engaged thereby and adjacent the side against which the wrapper has been previously folded by said transverse movement, said last-mentioned means being provided with a narrow slot therein to receive the corner flap produced by the folding operations described.

12. In a machine for folding a wrapper about a rectangular article, a folding member comprising a plate for folding a flap against the surface of said article, said plate having a slot therein arranged substantially at right angles to one edge thereof for receiving a corner flap formed by the folding of said wrapper by said plate, and means for moving said article relative to said slot

to cause said corner flap to be folded against the face of said article.

13. In a wrapping machine, means for folding a wrapper against two adjacent faces of an article to be wrapped, and means for folding a projecting portion against a third face of said article, said last-mentioned folding means comprising a plate having a surface for holding said projecting portion against said third face and having a slot therein arranged to provide an opening in said plate positioned, during said folding operation, in the plane of one of the first-mentioned surfaces of said article for receiving the corner flap produced by said folding operation.

14. In a wrapping machine, means for folding a wrapper about the corner of an article formed by two adjacent faces thereof, means for folding a projecting portion of said wrapper against a third face of said article which meets the two faces previously engaged by said wrapper, said last-mentioned folding means being provided with an opening for receiving the corner flap formed by said folding operation, and means for moving said article relative to said opening to fold said corner flap against the face of said article.

15. In a wrapping machine, a slideway having an opening for admitting an article thereto to be wrapped, a support arranged to move across said opening with an article thereon, means for interposing a wrapper across said opening, means for withdrawing said support from beneath said article, means for causing said article to engage said wrapper and to be moved transversely thereto into said slideway, and means for holding said wrapper against a face of said article during the movement of said article into said slideway to prevent relative movement between said article and said slideway.

16. In a wrapping machine, a slideway having an opening for admitting an article thereto, means for interposing a wrapper in the path of said article as it is moved into said slideway, means for supporting said article during the movement thereof in said slideway, and a device for moving said article along said slideway, said device being bifurcated to permit said support to pass between the bifurcations thereof.

17. In a wrapping machine, a slideway, a pusher for moving articles along said slideway, and a rearwardly extending projection on said pusher to assist in forming corner flaps on a wrapper being folded about said articles.

18. In combination, a slideway having side flanges, means for moving an article into said slideway to cause said side flanges to fold a wrapper, said side flanges having

slots therein in position to lie adjacent one folded about said article, stationary abutments for engaging said wrapper to perform said further folding, and a device arranged to move transversely of the direction of movement of said article to assist in said further folding. 65

19. In a wrapping machine, a slideway having side flanges, means for moving an article transversely to the direction of said slideway to position said article in said slideway, means for interposing a wrapper in the path of movement of said article as it enters said slideway so that projecting portions of said wrapper will be engaged by said side flanges and fold against said article, said flanges having slots therein for receiving corner folds in said wrapper, and means for moving said article along said slideway so that the corner folds in said slots will be folded over against the faces of said article. 70

20. In a wrapping machine, a slideway having side flanges with slots therein, mechanism for positioning an article in said slideway and for partially folding a wrapper about said article so that corner folds in said wrapper will project through said slots, means for moving said article along said slideway, and a stationary device for engaging said wrapper during the movement of said article in said slideway to further fold said wrapper about said article to permit folding of said corner folds by the edges of said slots without tearing said wrapper. 75

21. In a wrapping machine, mechanism for folding a wrapper about three consecutive sides of an article to be wrapped so that said wrapper projects over the edges of said sides, and means for folding the projecting edges against a face of said article in continuous succession about the periphery of said face. 80

22. In a wrapping machine, a slideway having side flanges thereon, means for moving an article into said slideway in a direction transverse to the direction of said slideway, means for interposing a wrapper in the path of movement of said article as it enters said slideway so that said wrapper will engage one face of said article and project therefrom on all sides of said face, means for engaging said wrapper to fold a projecting portion thereof against the front face of said article as it moves into said slideway, a pusher for engaging said wrapper to fold a projecting portion thereof against the rear face of said article while other projecting portions of said wrapper are folded by said flanges against the side faces of said article, means for moving said pusher to carry said article along said slideway to cause said wrapper to be further

23. In a wrapping machine, a slideway, means for moving an article into said slideway and partially folding a wrapper thereabout, a pusher for engaging the rear face of said article and for folding a projecting portion of said wrapper against said face, and a second pusher for engaging said rear face and for folding another part of said wrapper against said face. 85

24. In a wrapping machine, a slideway, means for moving an article into said slideway and for partially folding a wrapper about said article, a pusher arranged to engage a projecting portion of said wrapper as said article is moved into said slideway and to fold said projecting portion against the rear face of said article, mechanism for actuating said pusher to move said article in said slideway, and a second pusher arranged to move transversely of the direction of movement of said article into engagement with the rear face of said article and to fold a portion of said wrapper against said face, and means for moving said pusher in the direction of said slideway to impart a further movement of said article along said slideway. 90

25. In a wrapping machine, a slideway, a pusher arranged to move transversely of the direction of said slideway to fold a portion of a wrapper against one face of an article in said slideway, and means for actuating said pusher to move said article along said slideway. 95

26. In a wrapping machine, a slideway having a cover plate therefor with a transverse opening and a longitudinal slot therein, a pusher plate for moving articles along said slideway, an arm for supporting said plate, means for actuating said arm to move said pusher plate through said opening in said slideway to engage an article therein, mechanism for moving said arm along said slot to force said pusher plate along said slideway beneath said cover plate to a position beyond said cover plate, and means for actuating said arm to withdraw said pusher plate from said slideway and return it outside of said slideway. 100

27. In combination, a slideway, a pusher for moving articles along said slideway, an arm for supporting said pusher, an elongated pivotal support for said arm, means for sliding said arm along said pivotal support to cause said pusher to move an article along said slideway, and means for oscillating said arm about said pivotal support 105

at different longitudinal positions thereon to move said pusher into and out of position to engage an article in said slideway, said oscillating means comprising an elongated 5 bar carried by said arm, and a reciprocating member having sliding connection with said bar.

28. In a wrapping machine, a slideway having an abutment arranged adjacent 10 thereto, means for positioning a wrapper on said abutment to project beyond an edge thereof, means for moving an article past the edge of said abutment and in contact with said wrapper to fold said wrapper 15 about one corner into contact with two adjacent faces thereof and with the edges of said wrapper projecting beyond the edges of said faces, a side wall for said slideway arranged to engage a projecting portion of 20 said wrapper as said article is moved into said slideway and to fold said projecting portion against a third face of said article adjacent said first-mentioned faces while said wrapper continues to project beyond 25 the edge of one of said first-mentioned faces, said side wall having a slot arranged therein in position to receive the projecting portion of said wrapper, and means for moving said article along said slideway to cause said 30 projecting portion to be moved by the edge of said slot into contact with the face of said article.

29. In a wrapping machine, a slideway having spaced lateral walls, a cover for said 35 slideway having an opening therein for receiving articles in said slideway, means for positioning a wrapper adjacent said opening, and means for moving an article through said opening into said slideway to cause said wrapper to be folded against 40 adjacent sides of said article, said lateral walls having vertically arranged slots therein positioned substantially in alinement with one edge of the opening in said cover and arranged to receive projecting portions 45 of said wrapper as an article is moved into said slideway.

30. In a wrapping machine, a slideway, a cover plate for said slideway having one 50 edge extending transversely of said slideway to form an abutment for folding a wrapper about an article moved past said edge into said slideway, and a side wall for said slideway having the upper edge thereof 55 terminating below said cover plate, said side wall having a vertical slot therein substantially in vertical alinement with said edge of said cover plate and arranged to receive a projecting portion of a wrapper 60 as it is folded about an article in said slideway.

31. In a wrapping machine, a slideway, a cover plate for said slideway having one edge thereof extending transversely of said 65 slideway, side walls for said slideway hav-

ing the upper edges thereof terminating below said cover plate, vertically arranged slots in said side walls substantially in vertical alinement with said edge of said cover plate, means for moving an article past said 70 edge of said cover plate into said slideway to partially fold a wrapper about said article and to cause projecting edges thereof to extend into said slots, and means for moving said article along said slideway to 75 simultaneously fold a portion of said wrapper against the upper face of said article and the projecting portions of said wrapper against lateral faces of said article.

32. In a wrapping machine, an abutment 80 member having a space thereunder for receiving a wrapper, and means for exerting pressure on a plurality of contacting articles to press one of said articles against said abutment member to support said article between said abutment member and a contacting article while a wrapper is positioned thereunder.

33. In a wrapping machine, an abutment 85 member having a space thereunder for receiving a wrapper, means for supporting a series of articles adjacent said abutment member and for moving said articles toward said abutment member to cause the endmost 90 article of said series to be clamped between said abutment member and the next adjacent article of said series to support said endmost article, and means for positioning a wrapper beneath said article while so supported.

34. In a wrapping machine, an abutment 100 member, means for supporting a series of articles adjacent said abutment member, means for moving said support to bring the endmost article thereon into contact with said abutment member and for withdrawing said support from beneath said endmost article to leave said article suspended between said abutment member and the next adjacent article of said series, and means for positioning a wrapper beneath said article.

35. In a wrapping machine, an abutment 105 member having side flanges thereon, means for supporting a series of articles adjacent said abutment member, and means for pressing an article of said series against said abutment member and between said side flanges, and means for withdrawing said supporting member from said article while so positioned.

36. In a wrapping machine, an abutment 115 member having side flanges thereon, means for supporting a series of articles adjacent said abutment member, means for shifting said supporting means to bring the endmost article thereon between said side flanges and against said abutment member so that said article is held between said abutment member and the next adjacent article of said 120 series, means for positioning said wrapper 125

130

- beneath said article while so held, and means for withdrawing said supporting means from beneath said article.
37. In a wrapping machine, an abutment member, a horizontally extending plate for supporting a series of articles adjacent said member, means for moving said plate to press the endmost article thereon against said abutment member, means for withdrawing said plate from beneath said endmost article to leave said endmost article suspended between said abutment member and the next adjacent article of said series, means for positioning a wrapper beneath said endmost article, and means for engaging the lower face of said wrapper to press said wrapper against said article.
38. In a wrapping machine, means for placing a wrapper in contact with an article so that a portion of said wrapper will project beyond said article, means for folding said projecting portion against a face of said article along one edge thereof, means for folding a second projecting portion of said wrapper against said face along an adjacent edge thereof so that said second mentioned portion overlaps said first mentioned portion, and means for folding a third projecting portion of said wrapper against said face along a third edge of said face adjacent said second mentioned edge so that said third projecting portion when folded will overlap said second mentioned projecting portion.
39. A wrapping machine comprising two means for folding a wrapper against two adjacent faces of an article so that the edge of said wrapper projects beyond the edges of said faces, means for folding a projecting portion of said wrapper against a third face of said article along one edge of said third
- face, means for folding said wrapper against a fourth face of said article, means for folding a second projecting portion of said wrapper against said third face to overlap said previously folded projecting portion, and means for folding a third projecting portion of said wrapper along the edge of said fourth mentioned face of said article so that the projecting portion last folded will overlap the secondly folded projecting portion.
40. In a wrapping machine, a runway for an article to be wrapped, means for moving an article into said runway to place a wrapper in contact with the lower and front faces of said article and to fold a projecting portion of said wrapper about the lower edge of a lateral face of said article to bring said projecting portion into contact with said lateral face, means for folding a projecting portion of said wrapper about a lateral edge of said front face to bring said projecting portion into contact with said lateral face and into overlapping relation with the projecting portion folded about the lower edge of said lateral face, means for moving said article along said runway, means for folding said wrapper against the top face of said article during said movement so that the edge thereof projects beyond said top face, and means for folding said last mentioned projecting portion against the aforesaid lateral face of said article and into overlapping relation with the projecting portion of said wrapper folded about the lateral edge of the front face of said article.

In testimony whereof I have signed my name to this specification on this 28 day of March, A. D. 1919.

MICHAEL J. MILMOE.
